ELECTRICAL SWITCH

Robert M. Bleakney and Everly J. Workman,
Albuquerque, N. Mex., assignors to the United
States of America, as represented by the Secre-
tary of the Navy

Application April 10, 1942, Serial No. 438,506

2 Claims. (Cl. 200—52)

1

This invention relates to electric switches, and, in particular, to an improved switch of the so-called "inertia" type, in which the circuit contact members thereof are operated as the switch body is subjected to acceleration.

One application of our invention is to an ordnance projectile within which the switch may be installed for the purpose of closing an electric circuit for detonating a powder charge within the projectile as the latter is accelerated upon being fired from a gun. It will be understood, however, that our improved switch may be utilized for other applications and that the appended claims should be so construed.

An object of our invention is to provide an improved type of inertia switch in which the switch contacts will be closed and locked in their closed position as the switch is subjected to acceleration.

Another object of our invention is to provide an inertia type switch in which an inertia contact member is initially spaced from a fixed contact member by an extensible tie member, the latter member being extended as the switch is subjected to a predetermined degree of acceleration, permitting the fixed and inertia contact members to move towards and engage each other.

Another object is to provide an inertia operated switch in which the inertia contact member is initially spaced apart from the fixed contact member by a tie member of ductile material, which, when the switch is subjected to a predetermined degree of acceleration will elongate to permit the inertia contact member to engage the fixed contact member of the switch.

A further object is to provide an inertia operated switch in which an inertia contact member is initially spaced apart from the fixed contact member by a closely coiled tie member which will be elongated as the switch is subjected to a predetermined degree of elongation, permitting the switch contact members to engage each other.

Still another object of our invention is to provide an inertia switch in which the inertia contact member is initially spaced apart from the fixed contact member by a closely coiled tie member of ductile material, the latter being permanently elongated as the switch is subjected to an acceleration, thereby permitting the fixed and inertia contact members to engage each other.

Another object is to provide an inertia operated switch utilizing a cupped fixed contact member and a cylindrical inertia contact member movable into engagement therewith, one of the contact members being provided with means for

2

locking the two together upon their engagement.

These and other objects of our invention will become more apparent from the detailed description to follow and from the drawings, in which:

Fig. 1 is a central longitudinal section of a preferred embodiment of our improved inertia operated switch when in its open-circuit position, the parts being shown in elevation;

Fig. 2 is a similar view, showing the switch in its closed-circuit position;

Fig. 3 is a central longitudinal section taken on the line 3—3 of Fig. 1, the parts again being shown in elevation;

Fig. 4 is a cross-section taken on the line 4—4 of Fig. 1;

Fig. 5 is a perspective view of the movable contact member; and

Fig. 6 is a cross-section taken on the line 6—6 of Fig. 2.

Referring now to the drawings, the switch comprises a support member 10 which may be made of any suitable insulating material. Included within support member 10 is an opening 12 composed of a series of axial bores 13, 14, 15 and 16, the last of which communicates with an outlet passage 17. The bores 13 to 16 are preferably of progressively smaller diameters, thereby producing a succession of stop shoulders 18, 19 and 20.

A tubular member 21 which, in the present embodiment, is made of metallic material, is provided with an upper portion 22 and a lower portion 23 of smaller diameter providing an offset 24 which is adapted to seat upon shoulder 18. The bottom face of the tubular portion 23 rests upon shoulder 19.

The fixed contact of our switch comprises a cupped member 25 which may be of copper or some other suitable electrically conductive material, and is positioned within the bore 16, the bottom of the cup resting upon shoulder 20. The open top of member 25 is chamfered at 26 and is spaced at 27 from the bottom of tubular section 23.

A conductor 28 may be soldered or otherwise secured to the bottom of the cupped contact member 25 and may be led out of the switch body through passageway 17. A similar conductor 29 may be likewise secured to the body of a copper sleeve 30 which is secured within the tubular section 22.

The metallic sleeve 30 is formed with oppositely positioned lugs 33 at the bottom thereof. The ends of the lugs are secured together to form

a closed loop to which is attached a bight portion 34 formed at one end of a closely coiled helix 31 which, in the present embodiment, is made of a highly ductile material such as soft copper.

The inertia contact member of our switch is a solid cylindrical member 32 which is provided with oppositely disposed axial grooves 39. An open link member 38 which is metallic and preferably resilient is secured to contact member 32 by the grooves 39. A bight portion 40 of the link 38 is coupled to a complementary bight portion 35 formed at the bottom end of tie member 31.

The inertia contact member 32 has a tapered surface 36 formed at the bottom to permit unimpeded entry into the cupped contact member 25 and one end 41 of the link member 38 is bent so that it projects beyond the cylindrical surface of contact member 32. Thus when contact member 32 enters cupped member 25, the projecting end portion 41 will score the inside of the cupped contact as at 42 and lock the contact members 32 and 25 together.

The operation of our switch will be obvious. Assuming that the switch is installed on the inside of a projectile, the contacts are in the position shown in Fig. 1, while the projectile is in a rest position. When the projectile is fired from a gun, however, the acceleration of the projectile and hence the switch will cause the inertia contact member 32 to exert a force upon the coiled tie member 31 in accordance with the equation

$$\text{Force} = \text{Mass} \times \text{Acceleration}$$

Being of a ductile material, the latter will be axially extended until its shape is substantially as illustrated in Fig. 2, permitting contact member 32 to enter cupped contact member 25 and complete a circuit between conductors 28 and 29 which may be provided to detonate a powder charge within the projectile. This circuit has not been illustrated as it does not form a part of our invention.

The size of the wire constituting the coiled tie member 31 and the internal diameter of the coil together with the combined masses of the cylinder 32 and link member 38 will of course be determined by the degree of acceleration involved. For example, where accelerations are of the order of 8,000 g, g being equal to the acceleration due to gravity, we have found the following to be satisfactory:

1. Tie member 31—soft copper-diameter .020"—internal diameter of coil .040"—5 turns
2. Link member 38—beryllium copper-diameter .031"
3. Combined mass of contact member 32 and link member 38=275 milligrams

While the embodiment of our invention which has been described represents a preferred form of our invention, it will be evident that modifications and changes therein may be made by those skilled in the art without departing from the spirit

and scope of our invention and from the appended claims.

Having thus set forth and disclosed the nature of our invention, what is claimed is:

1. In a projectile including an electric circuit therein, an inertia switch carried internally of said projectile for controlling said circuit comprising a support, a cupped fixed contact member carried by said support, a complementary cylindrical contact member adapted to be received in said cupped contact member, a coiled ductile tie member, one end of which is connected to said support and the other end to said cylindrical contact member for initially spacing said contact members apart, said cylindrical contact member being movable when said projectile is subjected to a predetermined degree of acceleration to axially extend said tie member and enter said cupped contact member, and locking means carried by one of said contact members to lock said contact members together as said contact members move into engagement with each other.

2. In a projectile including an electric circuit therein, an inertia switch carried internally of said projectile for controlling said circuit comprising a support, a cupped fixed contact member carried by said support, a second complementary inertia responsive cylindrical contact member adapted to be received by said fixed contact, said second contact member including a pair of oppositely disposed axial grooves therein and an open link member carried in said grooves with one end of said link member projecting beyond the cylindrical surface of said second contact member, and a coiled ductile tie member, one end of which is connected to said support and the other end to a bight portion of said link member to initially space said contact members apart, said second contact member being movable when said projectile is subjected to a predetermined degree of acceleration to axially extend said tie member and enter said cupped contact member whereby the end of said link member projecting beyond the cylindrical surface of said second contact member will score the inner surface of said cupped contact member, causing said contact members to be locked together.
